SOUND REPRODUCING UNIT AND METHOD
FOR MAKING THE SAMEGilbert E. Gustafson, River Forest, Ill., assignor
to Zenith Radio Corporation, a corporation of
Illinois

Application April 23, 1943, Serial No. 484,153

16 Claims. (Cl. 179—107)

This invention relates to sound reproducing devices and a method for making the same.

In many sound reproducing systems, and especially in hearing aid apparatus, it is essential that the sound reproducing unit be of small size, inexpensive and of sturdy construction. Heretofore these desiderata were not always attained, because much skill and time were required to provide the correct air gap distance between actuating magnets and the associated movable diaphragm, because the parts of the system were of small dimensions, and because there was a large number of parts making up the composite sound reproducing unit.

It is therefore an object of this invention to provide a small, compact, inexpensive and sturdy sound reproducing unit especially suitable for use in hearing aids.

Another object of this invention is to provide a new and improved sound reproducing unit in which there is provided an air gap between actuating magnets and associated diaphragm of accurate dimension, which gap is maintained fixed with a high degree of stability.

Another object of this invention is to provide a small, compact, sturdy sound reproducing unit having a minimum number of parts.

Another object of this invention is to provide a new and improved method for assembling the parts of a sound reproducing unit which lends itself to mass production and yet insures a constant and stable air gap distance between actuating magnets and diaphragm.

This is the parent of a divisional application, filed March 11, 1944, Serial No. 526,094, in which claims are directed particularly to the process of making sound reproducing units described herein.

The features of my invention which I believe to be novel are set forth with particularity in the appended claims. My invention itself, both as to its organization and manner of operation, together with further objects and advantages thereof, may best be understood by reference to the following description taken in connection with the accompanying drawing in which:

Figure 1 is an exploded view of one embodiment of my invention;

Figure 2 is a perspective view of the assembled embodiment of Figure 1;

Figure 3 is a sectional view taken substantially on line 3—3 of Figure 1 when all of the elements shown in Fig. 1 are mounted on base 10;

Figure 4 is an exploded view of a jig for use in practicing the method of my invention to produce a unit as illustrated in Figure 1;

Figure 5 is a sectional view taken substantially on line 5—5 of base 10 in Figure 6 in the absence of pole pieces 11A, 12A and yoke 13.

Figure 6 is a perspective view showing apparatus for moulding the base of the unit shown in Figure 1, the section through the base being of a partially assembled unit as produced by the cementing process in Fig. 7;

Figure 7 is a view partly in elevation and partly in section showing the assembled jig of Figure 4 mounted with the cooperating base member 10 illustrated in Figure 1 arranged to practice the method of my invention, the sectional part being taken on a line corresponding to lines 7—7 of both Figs. 4 and 6.

Referring to Figure 1, the sound reproducing unit comprises a base 10, pole pieces 11 and 12, permanent magnet yoke 13, magnet coils 14 and 15, terminals 16 and 17, diaphragm 18 and cover 20 19.

The base 10 is of insulating material, such as Bakelite or the like, and has an inner circular ledge 20 upon which the diaphragm 18 normally rests. The base 10 has also a second lower inner ledge 21 upon which the terminals 16 and 17 are fastened (preferably by means of screws 16A and 17A or the like), and still lower oppositely disposed ledges 22 and 23 (see Fig. 6) upon which the magnet coils 14 and 15 rest. The base 10 has also a centrally located recess 24 in which the pole pieces 11 and 12 and yoke 13 are snugly received and in which they are fastened by means to be described later. The base 10 has two parallelly extending and integrally formed portions 25 and 26 in each of which is a hole adapted to receive a rod shaped electrical contact member (not shown), so that such electrical contact members, when inserted in the portions 25 and 26, make electrical connection with the terminal portions 27 and 28 of terminals 16 and 17, which portions 27 and 28 extend through base holes 29 and 30 (see Fig. 6) into the portions 25 and 26 of the base 10.

The base 10, of Bakelite or other similar material capable of being molded in suitable form and shape to form the various ledges and recesses and integrally formed projecting portions, is formed between a pair of cooperating dies 60 and 61 in Fig. 5, the inner surface 62 of die 60 being of the same shape as the outside surface of base member 10 and the outer surface 63 of die 61 having the same contour as the inner portion of base member 10.

In the manufacture of base member 10, a predetermined amount of unheated Bakelite, resin

or similar material is placed in die 60, the die 61 is then placed in cooperating relationship with die 60 with the Bakelite or similar moldable material therebetween, and the Bakelite is caused to solidify by applying heat thereto in well-known manner, with the result that when the dies 60 and 61 are separated from each other and from the solid Bakelite, base member 10 is produced. Terminal holes are then drilled by conventional means in base portions 25 and 26 for a purpose described later.

The yoke 13 is of magnetic material, preferably Alnico, an alloy of iron, aluminum, nickel and cobalt, in such proportions that the alloy has great permanence and coercive force. It abuts against and holds the pole pieces 11 and 12 in spaced relationship.

The magnet coils 14 and 15 are wound on bobbins 14A and 15A which have rectangularly shaped hollow cores 14B and 15B which may be pressed over the smaller portions 11A and 12A of pole pieces 11 and 12 which extend therethrough.

The diaphragm 18 comprises a thin disk having concentrically mounted thereon a smaller disk 18A sufficient to increase the central thickness of the diaphragm 18 so that it can carry the magnetic flux from yoke 13 and coils 14 and 15 without undesirable saturation.

The cover 19 has a circular shoulder 19A (see Fig. 3) adapted to engage tightly against the inner wall of base 10 but not of sufficient vertical extent to bottom against diaphragm 18. It also has an extending tubular projection 19B adapted to receive a sound transmitting element. In operation, the cover 19 is substantially stationary and the sound impulses generated by movement of diaphragm 18 are transmitted through cover opening 19C.

The pole pieces 11 and 12 and yoke 13 are cemented in and to the base 10 by a suitable material such as an alloy as shown in Fig. 3. One suitable low melting point alloy includes bismuth and lead. Its melting point is 255° Fahrenheit, and its casting temperatures range from 270° to 310° Fahrenheit. Instead of shrinking on solidifying, it expands slightly. Materials similar to this alloy, and which may be used in the cementing operation, are described on pages 184 and 185 of "Materials Handbook," by George S. Brady, published by McGraw-Hill Book Company, Inc., 1940.

In the assembling operation, some of the alloy material or cement is placed in recess 24 and on base ledges 22 and 23. The alloy material is then heated, preferably by induction heating (see coil 42 in Fig. 7), and, when the alloy cools, the yoke 13 and pole pieces 11 and 12 are held firmly in place in and on the insulating base 10. The bobbins 14A and 15A supporting coils 14 and 15 are then pressed onto pole tips 11A and 12A, and terminals 16 and 17 are then fastened on ledge 21, preferably by screws or rivets, with the terminal projecting portions 27 and 28 extending into the base portions 25 and 26, whereby electrical contact may be made with them when rod shaped electrical conducting members (not shown) are inserted into the holes in base portions 25 and 26. The diaphragm 18 is then placed on base ledge 20 and is held thereon due to the action of the magnetized pole pieces 11 and 12. The cover 19 is then placed on the base and is frictionally held in place thereby, the assembled unit appearing as in Figure 2.

The parts cemented preferably have prepared surfaces thereon so as to increase the area of the cemented surface and so as to provide a finished structure, having increased strength. That is for this purpose, the pole pieces 11 and 12 are provided with notches 11B and 12B respectively, the yoke 13 is provided with surfaces 13A having indentations 13B therein, and the base 10 is provided with indentations 10A therein which may partake of a grooved surface.

In order to make the sound reproducing unit heretofore described in mass production and with a predetermined constant distance between pole pieces 11 and 12 and diaphragm 18, the jig shown in Figure 4 is utilized. It is important to realize that in small hearing aid reproducing units the pole pieces 11 and 12 are mounted approximately .01 inch below base ledge 20 upon which diaphragm 18 rides; and, the diaphragm and outer pole piece surfaces must be substantially parallel with their separation tolerance in the order of a few percent.

The jig of Figure 4 comprises a circular base plate 31 of such outer diameter as to be frictionally held by the upper inner curved wall of the base 10. Shoulder 32 on base plate 31 serves to limit the movement of base plate 31 into base 10. In the exploded view, Figure 4, the rectangular shaped collar 33 is adapted to contain snugly within its hollow portion the wedge 34, the pair of channel shaped wedge members 35 and 36, and parts 11A and 12A of the pair of pole pieces 11 and 12.

In order to assemble the parts on the jig, the channel shaped wedge members 35 and 36 and parts 11A and 12A of pole pieces 11 and 12 are mounted on the base plate 31 within the rectangular ring 33, with channel shaped wedge members 35 and 36 in abutting relationship to the downwardly extending portions 11A and 12A of pole pieces 11 and 12. Then the screw 40 (Fig. 7), having wedge shaped head 34, is drawn against the cooperating channel shaped wedge members 35 and 36 by turning the nut 41. As nut 41 is tightened on screw 40 wedge shaped head 34 is drawn into engagement with cooperating wedge surfaces on channel members 35 and 36, and the resulting outward movement of channel members 35 and 36 causes parts 11A and 12A of pole pieces 11 and 12 to be firmly held in the encircling rectangular shaped ring 33. Magnetic yoke 13 is then placed on ring 33 between the downwardly extending portions 11A and 12A of pole pieces 11 and 12 its magnetism holding it securely between pole pieces 11 and 12.

The assembled jig is of such dimensions that when it is inserted in the base 10, containing the elements of the sound reproducing unit (such assembly being shown in Fig. 7), the shoulder 32 abuts the upper ledge 20 of base 10 (Fig. 6) with the pole pieces 11 and 12 and yoke 13 inserted in base recess 24 in predetermined spaced relationship to the base ledge 20 after the alloy material disposed between the base 10 and yoke 13 and pole pieces 11 and 12 melts.

It is noted that the alloy material initially placed in base 10 prior to inserting the jig therein is usually in powdered form thus causing shoulder 32 to be separated a small distance from the upper ledge 20 of base 10 when such jig is inserted into the base. But, when and as such powdered alloy melts, shoulder 32 approaches its position on the upper ledge 20 of base 10 either due to gravity forces acting on the composite 76 jig due to other forces applied between base 10

and the jig. Ultimately shoulder 32 rests on the upper ledge 20 of base 10 and is held in that position when and as the alloy later solidifies due to gravity forces acting on the composite jig or due to an external force applied between the jig and base member 10.

When high frequency current is applied to the coil 42 (Fig. 7) the low melting point alloy material (or another suitable material), which was initially placed in base member 10 around pole pieces 11 and 12 and yoke 13, melts. Then, as the alloy material cools and solidifies after coil 42 is deenergized, the alloy material expands slightly while shoulder 32 is firmly held on the upper ledge 20 of base member 10 and when the alloy material solidifies entirely, it firmly holds the pole pieces 11 and 12 and yoke 13 to the base 10 with the faces of pole pieces 11 and 12 in a predetermined spaced relationship with respect to the base ledge 20 upon which the diaphragm 18 is subsequently placed.

It is also noted that when the expansible metal alloy is heated by high frequency currents flowing in coil 42, eddy currents flowing in such expansible metal produce a magnetic shielding effect on pole pieces 11 and 12 and magnetic yoke 13 whereby less heat is generated in pole pieces 11 and 12 and yoke 13 due to high frequency currents in coil 42 than that produced when the expansible metal is absent. This feature is of particular importance since the magnetic state of pole pieces 11 and 12 and yoke 13 is disturbed much less when eddy currents flow in the expansible metal than is the case when such expansible metal is absent. After the pole pieces 11 and 12 and yoke 13 are thus cemented to the base 10, they are disengaged from the jig by loosening nut 41 on screw 40.

In the preferred embodiment of this invention, the pole pieces are cemented to the insulating base 10 by alloy material which is heated by high frequency induction heating apparatus.

It is also apparent that the alloy material may be heated by means other than by the preferred use of electrical induction heating apparatus and this invention is not necessarily limited to the preferred heating apparatus.

The fact that the preferred alloy material has a low melting point, is metallic and expands as it solidifies makes it a desirable cementing agent in this application. The fact that the material is metallic in nature allows the use of induction heating apparatus and the surrounding parts need not be unnecessarily heated because of an eddy current shielding effect produced by currents flowing in such material. Of importance is the fact that, since the alloy material expands as it solidifies, the pole pieces 11 and 12 are pressed and tend to move outwardly, thus assuring predetermined spacing of the pole pieces 11 and 12 with respect to base ledge 20. In order to achieve this particular feature, it is of course necessary to place a sufficient quantity of such alloy material between the base 10 and pole pieces 11 and 12 in the assembling operations, such sufficient quantity being of a thickness greater than the thickness present in the finished product, heating such material above its melting point and constraining the flow of such material to a degree as it solidifies such that the pole pieces 11 and 12 are firmly pressed and tend to move outwardly against the force of gravity or other external forces which act to maintain shoulder 32 in abutting relationship to the upper edge of base 10, thus assuring predetermined spacing

of the pole pieces 11 and 12 with respect to base ledge 20. It is noted that since the base recess 24 snugly receives the pole pieces 11 and 12 and yoke 13, a small clearance exists between the walls defining recess 24 through which the material may pass with appreciable resistance as it solidifies and consequently a relatively large force is exerted by the expanding material between base 10 and pole pieces 11 and 12. This expanding force is utilized in accordance with the present invention to avoid voids and to establish an accurate air gap distance.

In the assembled jig the parts 11A and 12A of pole pieces 11 and 12 abut the base plate 31 and are of predetermined height, so as to assure their correct spacing in the fabricated sound reproducing device, the height of shoulder 32 on base plate 31 of the jig being just right to assure such correct spacing.

20 The cementing process described herein is accomplished by making use of the adhesive or binding properties of materials which set in cementing relation between the parts to be cemented whereby those parts can be placed in predetermined space relationship, as in a jig, and held in such relation when the cement sets. The cementing process is preferably carried out by using a low melting point material having the property of expanding as it cools, and in which the material adheres to the parts being cemented in the insulating base.

25 Furthermore, it is noted that since pressure is applied to the expansible alloy when and as it solidifies it is reasonable to believe that such alloy is in a somewhat stressed condition after the complete solidification process.

30 While I have shown and described particular embodiments of my invention, it will be obvious to those skilled in the art that changes and modifications may be made without departing from my invention in its broader aspects, and I, therefore, aim in the appended claims to cover all such changes and modifications as fall within the true spirit and scope of my invention.

35 I claim:

1. In a sound reproducing unit, a base member of insulating material, and a pole piece fixedly mounted on said base in predetermined spaced relationship thereto by metallic cement having the property of expanding as it solidifies.

2. In a sound reproducing unit, a base member of insulating material having a ledge, and a pole piece fixedly mounted by cement on said base in predetermined spaced relationship to said ledge, said cement being a metal having the property of expanding as it solidifies.

3. In a sound reproducing unit, a base member having a recess and a ledge, a pair of pole pieces, a magnetic yoke abutting against said pole pieces and holding said pole pieces in spaced relationship, said pole pieces and yoke being disposed in said recess and fixedly mounted by cement on the base member with the faces of said pole pieces lying in predetermined spaced relationship to the ledge, said cement being of metal having the property of expanding as it solidifies.

4. In a sound reproducing unit, a base member of insulating material having a circular ledge and a recessed portion, a pair of pole pieces, a magnetic yoke abutting against said pole pieces, said recess being arranged to snugly receive said pole pieces and yoke, a magnetic coil for each one of said pole pieces, said base member having a pair of oppositely disposed ledges each supporting one of the magnet coils, a thin layer of metal

cement having the property of expanding as it solidifies in said recess between said pole pieces, yoke and base member, said layer of metal cement providing the sole means for fastening the pole pieces and yoke to said base, said metal cement being of predetermined thickness for accurately spacing said pole pieces in said base.

5. In a sound reproducing unit, a base member of insulating material having a circular ledge and a recessed portion, a pair of pole pieces, a magnetic yoke abutting against said pole pieces, said recess being arranged to snugly receive said pole pieces and yoke, a magnet coil for each one of the pole pieces, said base member having a pair of oppositely disposed ledges and each supporting one of the magnet coils, a thin layer of metal cement having the property of expanding as it solidifies in said recess and disposed between said pole pieces, yoke and magnet coils and providing the sole means for fastening the pole pieces in predetermined spaced relationship to the first mentioned ledge, said metal cement being of predetermined thickness for accurately spacing said pole pieces in said base, said base member having a pair of parallel extending hollow portions, a terminal for each one of the magnet coils, said base member having a pair of oppositely disposed ledges each adapted to support one of the terminal members, said base member having a channel extending from each of the last mentioned ledges to each one of the hollow portions, and said terminals each having a projection extending through each channel and into the corresponding base hollow portion.

10. In a sound reproducing unit, a base member having a recess, a pair of pole pieces, a magnetic yoke abutting said pole pieces and holding said pole pieces in spaced relationship, said pole pieces and yoke disposed in said recess and fixedly mounted by cement on the base member in predetermined spaced relationship in said base, said cement being a metal having the property of expanding as it solidifies.

15. In a sound reproducing unit, a base member having a recess, a pair of pole pieces, a magnetic yoke abutting against said pole pieces and holding said pole pieces in spaced relationship, said pole pieces and yoke being fixedly mounted by cement in said recess, and said pole pieces, yoke and base member having cooperating surfaces thereon adapted to readily hold said cement, said cement being a metal having the property of expanding as it solidifies.

20. In a sound reproducing unit, a base member of insulating material, a pole piece in said base in predetermined spaced relationship therein, a thin layer of metal cement having the property of expanding as it solidifies and in a stressed condition disposed between the pole piece and base and providing the sole means for fastening the pole piece to the base, said metal cement being of predetermined thickness for accurately spacing said pole piece in said base.

25. In a sound reproducing unit, a base member of insulating material having a ledge, a pole piece in predetermined spaced relationship to said ledge, a thin layer of metal cement having the property of expanding as it solidifies disposed between the pole piece and base and providing the sole means for fastening the pole piece to the base in predetermined spaced relationship to said ledge, said metal cement being heatable to its melting point by induction heating and being of predetermined thickness for accurately spacing said pole piece with respect to said ledge.

30. In a sound reproducing unit, a base member of insulating material, a pole piece in said base in predetermined spaced relationship therein, a thin layer of metal cement having the property of expanding as it solidifies and in a stressed condition disposed between the pole piece and base and providing the sole means for fastening the pole piece to the base, said metal cement being of predetermined thickness for accurately spacing said pole piece in said base, said thin layer of metal cement being heatable by induction heating to its melting point.

35. In a sound reproducing unit, a base member of insulating material having a ledge, a pole piece in predetermined spaced relationship to said ledge, a thin layer of metal cement having the property of expanding as it solidifies disposed between the pole piece and base and providing the sole means for fastening the pole piece to the base in predetermined spaced relationship to said ledge, said metal cement being heatable to its melting point by induction heating and said metal cement being so disposed that eddy currents flowing therein when inductively heated reduce the heating of said pole piece, said cement being of predetermined thickness for accurately spacing said pole piece with respect to said ledge.

40. In a sound reproducing unit, a base member of insulating material, a pole piece in said base in predetermined spaced relationship therein, a thin layer of metal cement having the property of expanding as it solidifies and in a stressed condition disposed between the pole piece and base and providing the sole means for fastening the pole piece to the base, said metal cement being of predetermined thickness for accurately spacing said pole piece in said base, said thin layer of metal cement being heatable by induction heating to its melting point, said metal cement being so disposed that eddy currents flowing in said cement when heated produce a substantial magnetic shielding effect on said pole piece whereby the heating of said pole piece is reduced substantially when said metal cement is inductively heated.

45. In a sound reproducing unit, a base member, a pole piece, and metallic cementing material therebetween having the property of expanding as it solidifies to assure a correct spacing of said pole piece with respect to a point on said base.

50. In combination, in a sound reproducing unit, a base member, a pole piece, means for producing variable flux in said pole piece, a diaphragm actuated in response to said flux variations and carried by said base member, and means including metallic cementing material having the property of expanding as it solidifies interposed between said pole piece and diaphragm carrying member to assure a correct spacing of said pole piece with respect to a point on said base.

55. A sound reproducing unit comprising resilient means composed at least in part of magnetic material for actuating the air to produce sound waves, electromagnetic means responsive to electric currents of voice frequency for producing a magnetic field to drive said resilient means, a base member supporting said resilient means and electromagnetic means in predetermined space relationship, said base member being composed at least in part of a metal alloy having a low melting point and the property of expanding as it freezes, said metal alloy and a portion of the 60 unit adjacent thereto being shaped so as to be

locked together against relative movement when said alloy is in a solid condition, thereby to maintain said predetermined space relationship.

16. A sound reproducing unit comprising resilient means composed at least in part of magnetic material for actuating the air to produce sound waves, electromagnetic means responsive to electric currents of voice frequency for producing a magnetic field to drive said resilient means, a base member of insulating material supporting said resilient and electromagnetic means.

and a spacer disposed between one of said means and said base member for accurately locating said means relative to each other, said spacer being composed of a low melting point electrically conductive alloy having the property of expanding as it freezes, and both of said means being positioned to one side of said spacer and electromagnetically shielded thereby from heating when said spacer is inductively heated.
